US0D1096307S

(12) **United States Design Patent** (10) **Patent No.:** **US D1,096,307 S**
(45) **Date of Patent:** **** Oct. 7, 2025**

(54) **CONTAINER LID**

(71) Applicant: **Runway Blue, LLC**, Lehi, UT (US)
(72) Inventors: **David Bytheway**, Springville, UT (US);
David O. Meyers, Layton, UT (US);
John R. Omdahl, II, Lindon, UT (US)
(73) Assignee: **Runway Blue, LLC**, Lehi, UT (US)

(**) Term: **15 Years**

(21) Appl. No.: **29/916,168**

(22) Filed: **Nov. 8, 2023**

(51) **LOC (15) Cl.** **07-01**

(52) **U.S. Cl.**

USPC **D7/392.1**; D7/396.2

CLAIM

The ornamental design for a container lid as shown and described.

DESCRIPTION

FIG. 1 is a top front isometric view of a container lid showing the claimed design;

FIG. 2 is a top rear isometric view thereof;

FIG. 3 is a bottom front isometric view thereof;

FIG. 4 is a front elevation view thereof;

FIG. 5 is a rear elevation view thereof;

FIG. 6 is a left-side elevation view thereof;

FIG. 7 is a right-side elevation view thereof;

FIG. 8 is a top plan view thereof;

FIG. 9 is a bottom plan view thereof; and,

FIG. 10 is a top front isometric view of the container lid in an environmental state of use with a straw.

The broken lines form no part of the claimed design and are shown for the purpose of illustrating unclaimed parts of the article and environmental subject matter.

1 Claim, 9 Drawing Sheets
